UNITED STATES PATENT OFFICE.

AUGUSTUS A. WEST, OF PHILADELPHIA, PENNSYLVANIA, ASSIGNOR TO MAGIC HAIR CURLER COMPANY, OF PHILADELPHIA, PENNSYLVANIA, A CORPORATION OF PENNSYLVANIA.

HAIR CURLER.

Application filed May 6, 1924. Serial No. 711,317.

To all whom it may concern:

Be it known that I, AUGUSTUS A. WEST, a citizen of the United States, and resident of the city of Philadelphia, county of Philadelphia, State of Pennsylvania, have invented certain new and useful Improvements in Hair Curlers, of which the following is the specification.

The device, the subject of this invention 10 is intended as a hair curler and is particularly adapted for use with bobbed hair.

An object of the invention is to provide means for engaging the ends of the hair and for so retaining the hair that the curler 15 may be rolled upon the hair.

Another object of the invention is to provide a curler that can be readily withdrawn from the hair without unrolling the curl and another object of the invention is to 20 provide means for retaining certain parts of the curler together, so that a clamping action may be obtained by means of the fingers and other objects and the details of the construction will be fully set forth 25 as the specification progresses and the accompanying drawing should be referred to for a complete understanding of the specification which follows.

In the drawing—

30 Fig. 1, is a plain view, showing my curler. Fig. 2, shows the curler in the first operation, that of engaging the hair.

Fig. 3, shows the curler with the hair rolled thereon.

35 Fig. 4, shows the curler bent to secure it to the hair.

Fig. 5, shows a curler with a part fractured to expose the interior, and

40 Fig. 6, shows a curler with a part fractured and with a different covering.

Similar reference numerals indicate like parts in all the figures where they appear.

My hair curler is formed of an integral 45 length of soft and readily flexible wire, bent at mid length to form a loop 10 and a plurality of arms 11 and 12, which may extend parallel, one with the other.

It is necessary in curling bobbed hair to 50 clampingly engage the ends of the hair or to engage the curler at a point approximating the ends of the hair and thereafter to roll the curler into the hair.

In my device, the clamping is made possible by securing the two arms together at a point inward from the looped end thereof 55 and for the purpose of securing the arms, I provide a strap or clamp as shown at 13, which should be immovably secured upon both arms, retaining the arms one upon the other. When the hair is rolled upon the 60 curler as shown in Fig. 3, the ends of the curler may be bent upward or inward upon the hair, thus preventing the curler unrolling or freeing itself from the hair.

When it is desired to remove the curler, 65 the arms are straightened out or returned to the position shown in Fig. 3, whereupon the curler may be withdrawn from the hair.

It is quite necessary that the curler be smooth, otherwise when it is withdrawn, 70 the interior of the curl will be pulled outward and the contour of the curl destroyed. I prefer therefore, that the curler shall be formed of soft metal, which may be enameled or it may be formed with a metallic core 75 as shown at 14 in Fig. 5 and a suitable covering, such as gutta percha as shown at 15 should be used. I may form my curler of a wire core member as shown at 16 in Fig. 6, arranged thereon a fabric covering as 80 shown at 17. If a fabric covering is used, I prefer that it should be impregnated with a permanently flexible enamel, so that the surface upon which the hair is wound will be quite smooth. 85

Modifications may be made within the scope of the appended claim, without departing from the principle or sacrificing the advantages of the invention.

Having carefully and fully described my 90 invention, what I desire to secure is:—

A hair curler formed of flexible wire and having a plurality of arms, a loop connecting the arms and means arranged inwardly from though adjacent to said loop for securing the arms permanently engaged one upon the other the ends of said arms being free and of uniform contour. 95

Signed at the city of Philadelphia, county of Philadelphia, State of Pennsylvania, this 100 29th day of April, 1924.

AUGUSTUS A. WEST.
